Attorneys.

UNITED STATES PATENT OFFICE.

CARL A. BRINK, OF CRANSTON, RHODE ISLAND, ASSIGNOR, BY MESNE ASSIGNMENTS, TO THE NEW ENGLAND TRUST COMPANY, A CORPORATION OF MASSACHUSETTS, TRUSTEE.

TENSION DEVICE.

Application filed December 19, 1921. Serial No. 523,553.

To all whom it may concern:

Be it known that I, CARL A. BRINK, a citizen of the United States, residing at Cranston, in the county of Providence, State 5 of Rhode Island, have invented certain new and useful Improvements in Tension Devices, of which the following is a specification.

My invention relates to improvements in 10 tension-devices for use with winding machines and other textile apparatus.

One object of the invention is to provide 15 a device of the type specified in which a more constant and uniform degree of tension may be applied to the running yarn, thread or other filament.

Another object of the invention is to provide 20 a tension-device in which the pressure of the tension-means is controlled without fluctuation and prevented from undue influence under jar or vibration of the machine 15 or other apparatus to which it is applied.

Another object of the invention is to provide 25 means for gradually varying the amount of tension applied to the yarn in accordance with a predetermined cycle of operations in the functioning of the machine to which the device is applied.

Further objects of the improvement are 30 set forth in the following specification which describes a preferred embodiment of the invention as illustrated in the accompanying drawings.

In the drawings: 35 Fig. 1 is a side elevation of my improved tension-device;

Fig. 2, a transverse sectional view of the same, taken on the line 2—2 of Fig. 1; and

Fig. 3, a plan view of the device in part 40 section on the line 3—3 of Fig. 1.

Referring to the drawings, my improved tension-device is herein shown as mounted 45 on a frame or bracket which, in its present embodiment, comprises two parts 4 and 5. The main part 4 of the bracket consists of a horizontal arm or support 6, from the outer end of which rises a vertical wall 7 having an extension 8 forming one half of a housing or cage for the tension-members 50 to be later described. The opposite part 5 of the bracket is complementary to the extension 8 and is fastened to the side of the wall or upright 7 by means of bolts or

screws 9. The base of the housing or cage is constructed in the form of a shelf 10, see 55 Fig. 2, which is inclined downwardly at its outer end, and rising from the edge of the shelf are two curved arms or rims 11.

Supported from the shelf portion 10 of the main bracket part 4 is a hub-like bearing 14 which is bored to receive a stud or pin 15 fastened therein by suitable means, such as a set-screw 13. The stud 15 serves as the bearing for a pair of rotatable tension-disks 16 and 17 constituting the pressure-elements which bear upon the yarn or thread *y* passing between the disks. As shown in Figs. 2 and 3, the tension-disks 16 and 17 are preferably constructed of sheet-metal blanks struck up in concavo-convex 70 form to provide that they bear against each other only at a point adjacent their peripheries. Outwardly beyond the bearing point of the disks their rims are flared away to provide a V-shaped entrance groove for the 75 yarn to facilitate the operation of drawing it into position between the sides of the disks. Referring to Fig. 2, the hub 14 which supports the bearing-stud 15 for the tension-disks is cupped out or recessed on 80 one side to adapt it to receive the end of a coiled spring 19. The spring 19 surrounds the stud 15 and bears at its opposite end against the side of the disk 17. Outwardly beyond the disks the stud 15 is formed with 85 an enlarged, cylindrical head 20 having an inclined or beveled face 21 disposed opposite the side of the outer disk 16. Extending in an axial direction through the head 20 is a small hole 22 adapted to receive the 90 end of a length of wire 24. The wire 24 is coiled into a ring 25 extending in a plane at right-angles to the axis of the stud 15 and terminating in an upright extension or finger 26. The ring 25 bears against the 95 side of a thin washer 27, preferably constructed of felt or similar yielding material, and the washer, in turn, bears against the side of the outer tension-disk 16. The wire 24 is slidable in the hole 22 in the head 20 100 and with its ring 25 constitutes a presser-member for acting against the disk 16.

At the left hand end of the main bracket-member 4 is an arm 28, see Figs. 1 and 3, which is provided with a counter-bored hole 105 29. An arm or lever 30, preferably formed

of wire rod, is provided with a bent portion 31 at its end hooked through the hole 29 and retained therein by a crook 32 at its extremity. Beneath the rod or lever 30 is 5 a finger 33 which serves as a rest therefor, while the opposite end of the lever is arranged to bear on the beveled face 21 of the head 20 of the stud 15 to engage with the finger 26 of the ring or presser-member 10 25. A lateral prying force is applied to the rod or lever 30 by means of weights 35 suspended thereon. As shown in Fig. 1, the weights 35 are carried on a spindle or skewer 36 having an eye 37 at the upper end for 15 suspending it on a hook 38. The hook 38 is bent into a loop 39 adapted to be hooked over the top of the lever 30, and provided with an extension or link 40 from which it may be manipulated to slide the weights 20 along the lever to vary their pressure on the tension-disks in the manner and for the purpose as hereinafter more fully explained. In some instances, where the device is to be used without requirement for automatic 25 variation in the amount of tension applied to the yarn, manual adjustment is effected by placing the weights on the lever in different positions in relation to the fulcrum of the latter. For this purpose the weight-hook 38 may be constructed without the extension or link 40 and the rod or lever 30 may be provided with notches with 30 which the hook engages in accordance with a well known arrangement. 35 It will be understood that by shifting the weights away from the fulcrum or pivot of the lever 30 the force of the latter will be augmented, whereby it will act against the beveled face 21 on the head 20 of the 40 stud 15 to apply increased pressure upon the ring 25 which bears against the tension-disk 16. Likewise, when the weights are shifted in the opposite direction, or toward the fulcrum of the lever 30, the force of 45 the latter is decreased to diminish the pressure on the disk 16. In winding machines for winding large cops or cones of thread or yarn it is a usual practice to reduce the tension applied to the yarn as the latter 50 travels at an increasing rate due to the increase in diameter of the package. Any suitable means may be employed for moving the weights along the pressure lever 30 and as generally provided such means are 55 operated from the receding movement of the thread-guide with respect to the axis of the package being wound. For instance, in U. S. Letters Patent No. 506,959, granted October 17, 1893, to Simon W. Wardwell, 60 a system of connected levers is used for effecting a shifting of the tension-weights to relieve the tension on the yarn as the cop or package increases in diameter; and in U. S. Letters Patent No. 682,770, granted 65 September 17, 1901, to the same inventor,

the movement of the traverse-frame which carries the thread-guide is employed in the same manner for varying the pressure applied by the tension-weights. In the present invention the tension-weights may be 70 shifted along the lever 30 by connecting the arm 40 to the traverse-frame of the winding machine, or any equivalent means arranged to be moved by the recession of the thread-guide during the growth in the cop being 75 wound. The method of operation of the complete device as herein illustrated is as follows:

The yarn, thread or other filament y may be supplied from a cop or bobbin, not herein shown, but usually placed below the tension-device, and leading up through a slot or opening 41 in the shelf 10 of the bracket 4, 5, see Figs. 2 and 3, is drawn in between the disks 16 and 17 and across the pin or stud 15, as shown in Fig. 1. From the stud 15 the yarn y leads to the winding machine or other apparatus where it is taken up in the process for which the machine is operated. As the yarn y draws across the axial pin 15 in a tangential direction in relation thereto it has a tendency to rotate the tension-disks 16 and 17 with a relatively slow motion. This action prevents the yarn from 80 wearing or cutting a groove in the faces of the disks as the latter are pressed against the yarn to resist its draft to apply the desired tension thereto. As before explained, the degree of tension applied to the yarn is 85 dependent upon the amount of pressure exerted by the lever 30 to force the disk 16 toward the disk 17, and this may be varied by shifting the pressure-weights 35 toward or away from the fulcrum of the lever. 90 As the weight of the weights 35 is applied to the lever 30 to cause the latter to be wedged laterally against the presser-ring 25 through the action of the beveled face 21 on the side of the lever. The pressure of the ring 25 95 against the side of the washer 27 acts on the disk 16 to force it toward the disk 17 and movement of the latter is resisted by the 100 spring 19. In this way a yielding pressure is applied to maintain the disks bearing upon the yarn y so that when knots, bunches 105 or enlargements thereon pass between the disks the latter will readily separate without exerting undue resistance to the draft of the yarn. This yielding action is accomplished by the contraction of the spring 19, 110 without requiring that the lever 30 be lifted or otherwise displaced, and therefore it is not required to lift the weights 35. Through 115 this provision the inertia of the weights remains undisturbed so that they are prevented from jumping or vibrating as in other previous devices where the pressure is applied through similar means. The tension-weights are thus caused to act with a 120 uniform and constant pressure whereby ir- 125 130

regularities are prevented, and thus an improved effect is produced in the tension applied to the yarn. Moreover, the provision of the weight-lever 30 bearing against the 5 beveled or inclined face 21 to force it against the member 25 which bears against the disk 16 further tends to steady the lever to prevent it from jumping or vibrating and in this way the effects of momentum and 10 inertia are eliminated and a smoother and more constant action secured.

Various modifications may be made in the form and construction of my improved device without departing from the spirit 15 or scope of the invention; therefore, without limiting myself to the precise embodiment herein shown and described, I claim:

1. In a tension-device, the combination with means adapted to bear upon a running 20 yarn or filament to apply tension thereto, of means to control the action of the tension-means comprising a movable member, means to apply pressure to the movable member and an element having a beveled face against which the movable member acts to exert a constant wedging thrust against the tension-means.

2. In a tension-device, the combination with means adapted to bear upon a running 30 yarn or filament to apply tension thereto, of a weighted member for applying pressure to said tension-means, and a fixed element provided with an inclined face against which the weighted member acts to wedge it against the 35 tension-means with a constant pressure.

3. In a tension-device, the combination with means adapted to bear upon a running yarn or filament to apply tension thereto, of means for exerting pressure on said tension-means comprising two coacting elements, one 40 fixed and the other yieldable and with one of said elements having a beveled face for wedging the other element toward the tension-member with a constant pressure.

4. In a tension-device, the combination with means adapted to bear upon a yarn or filament to apply tension thereto, of a weighted member for applying pressure to the tension-means, and a fixed member 50 against which said weighted member acts, said fixed member being provided with a beveled face against which the opposite member acts to convert the force of the weighted member into a wedging action to apply a constant uniform pressure to the tension-means.

5. In a tension-device, the combination with means adapted to bear upon a yarn or filament to apply tension thereto, of a fixed 60 element provided with an inclined face, and a movable element operated under pressure to act against said face to exert a constant wedging thrust upon the tension-means.

6. In a tension-device, the combination 65 with opposite tension-members adapted to

bear upon a running yarn or filament drawing therebetween, of a lever for applying pressure to said tension-members to force them together, and means provided with an angular face against which the lever acts to 70 cause it to exert a wedging thrust on the tension-members to apply a constant pressure thereto.

7. In a tension-device, the combination with opposite tension-members adapted to 75 bear upon a running yarn or filament drawing therebetween, of resilient means for pressing against one of said tension-members, and means for applying pressure to the opposite tension-member comprising two co-acting elements one fixed and the other movable and one of which is provided with an inclined face for exerting a constant wedging force against the other element.

8. In a tension-device, the combination with a pair of tension-members, of means for yieldingly supporting said members to adapt them to bear upon a running yarn drawing between them, and a pair of coacting elements one fixed and the other movable and having wedging engagement one with the other to adapt them to exert a constant pressure to cause the tension-members to press upon the yarn.

9. In a tension-device, the combination 95 with a bearing-stud, of a pair of tension-disks mounted on said stud, a lever adapted to bear laterally against the disks to apply pressure thereto, and means provided with a beveled face with which the lever engages to cause a constant lateral thrust thereon.

10. In a tension-device, the combination of a stud formed with an enlargement at its end provided with a beveled face on its side, a pair of tension-disks mounted on said stud, and pressure-operated means acting against the beveled face on the stud to wedge against the tension-disks to apply a constant lateral thrust thereon.

11. In a tension-device, the combination 110 with a pair of tension-disks, of a member provided with a bearing face arranged in inclined relation to the side of the disks, and a pressure-member adapted to bear against the inclined face to cause the pressure-member to be thrust laterally against the tension-disks with a constant pressure thereon.

12. In a tension-device, the combination with a bearing stud, of a pair of tension-disks mounted on said stud, resilient means bearing against the side of one of the disks, pressure-means adapted to press against the side of the opposite disk, and a fixed element having an inclined face against which said pressure-means acts to cause said pressure-means to be displaced laterally to exert a thrust on the tension-disks with a constant pressure thereagainst.

13. In a tension-device, the combination 130 with a pair of tension-disks, of a pivoted

lever adapted to apply lateral pressure upon the disks, a fixed element provided with an inclined face against which the lever acts, and weights adjustable on the lever to vary its pressure on the disks.

14. In a tension-device, the combination of a stud having a head formed with a beveled face on its side and a hole extending parallel with its axis, a pair of tension-disks mounted on the stud, a wire slidable in the hole in the head of the stud and provided with a coiled extension bearing against the side of one of the disks, and a lever adapted to engage the beveled side of the head of the stud to cause it to exert a lateral thrust on the wire coil to press the latter against the tension-disks.

15. In a tension-device, the combination

with a stud provided with a bevel-sided enlargement at its end, a pair of tension-disks mounted on said stud, a ring bearing against the side of one of the disks, and pressure means acting against the beveled face of the stud to force it against the ring to apply a lateral thrust on the tension-disk.

16. In a tension-device, the combination with a stud provided with a beveled head at its end, a pair of tension-disks mounted on said stud, a resilient washer bearing against the side of one of the disks, a ring bearing against the washer, and pressure means engaging the beveled head of the stud to force it against the ring to cause the latter to exert pressure on the disk.

In testimony whereof I affix my signature.
CARL A. BRINK.
